WINDOW SCREEN CATCH

Julius Freeland, Kansas City, Mo.

Application January 10, 1945, Serial No. 572,142

1 Claim. (Cl. 292—218)

1

My invention relates to improvements in window screen catches.

One of the objects of my invention is to provide a novel window screen catch, which may be easily and quickly applied to any ordinary window screen, which will firmly hold the screen in its proper closed position, which is simple, cheap to make and install in its operative position, which is durable, and is efficient in its operation.

The novel features of my invention are hereinafter fully described and claimed.

In the accompanying drawing, which illustrates the preferred embodiment of my invention,

Fig. 1 is a side view of my improved screen catch shown in operative locking position between a window screen frame and the sash, parts being shown in elevation, parts in vertical section, and parts broken away.

Fig. 2 is a top view of part of what is shown in Fig. 1.

Fig. 3 is an inside elevation of what is shown in Fig. 2.

Similar characters of reference designate similar parts in the different views.

1 designates an ordinary window sill, 2 a window screen frame above the window sill, and 3 the lower window sash at the inner side of the screen frame and spaced therefrom.

4 designates a latch member, which in the form shown comprises a cylindrical rod having a hand engaging hook 5 at its inner end. Means are provided for pivoting the outer end of the latch member to the inner side of the screen frame 2, which means, as shown, comprises a screw eye 6 mounted in the inner side of the frame 2 and having its eye pivotally engaged with an eye 7 on the outer end of the latch member 4.

The latch member 4 has extending horizontally through it a transverse pin having projecting ends which form detent arms 8 disposed intermediate of the hand hook 5 and the eye 7.

A ratchet member is provided for releasably engaging the arms 8 of the latch member 4, for holding the latter in the locking position, holding the lower end of the screen frame 2 against the upper side of the slanting portion of the window sill 1.

Such ratchet member in the form shown comprises a preferably resilient metal plate 9 having two spaced apart upstanding portions 10, each having on its inner side, one above the other, a plurality of ratchet teeth 11 adapted to be in the path of one of the detent arms 8 and to be en-

gaged releasably successively and lockingly by said arm, when said latch member 4 is swung downwardly between the portions 10 to the locking position, as shown in the drawing. The ratchet member 9 is provided with means adapted to securely hold it in the operative position, above described, which, as shown, comprises an angular base portion 12, adapted to be fastened, as shown, to the upper side of the sill 1, between 10 the screen frame 2 and the sash 3 by two screws 13.

In operation, the screen frame 2 is pulled inwardly by the operator holding the hooked end of the latch member 4, until the lower end of the frame 2 strikes the slanting upper side of the sill 1. The latch member 4 is then swung downwardly between the upstanding portions 10 of the ratchet member 9. In such downward movement, the detent arms 8 will respectively engage 20 the ratchet teeth 11 of the two rows successively until the detent arms are lockingly engaged with two of the teeth respectively. To release the screen frame 2, the upper end portions of the portions 10 are forced outwardly, releasing the 25 detent arms 8, after which the latch member 4 is swung upwardly from its engaging position with the ratchet member.

Many modifications of my invention, within the scope of the appended claim, may be made without departing from the spirit of my invention.

What I claim is:

In a window screen catch, in combination with a latch member having a lateral arm, of means adapted to pivot said latch member on a horizontal axis to the inner side of a window screen frame, a ratchet member comprising a resilient plate having an upstanding portion with a plurality of ratchet teeth, one above the other, and means adapted to attach the lower portion of said 35 ratchet member to the upper side of the window sill spaced from and at the inner side of the screen frame, and in a position in which said ratchet teeth will extend inwardly and will be successively struck and pressed outwardly, with said upstanding portion, by said arm, when said latch member is swung downwardly with said arm at the inner side of said upstanding portion, said upstanding portion being sprung forwardly manually when it is desired to free said latch member 40 and permit its upward swinging to a release position.

JULIUS FREELANDER.
